METHOD OF PRODUCING BUTADIENE FROM
PETROLEUM AND PETROLEUM FRAC-
TIONSArno Brasch, New York, N. Y., assignor, by mesne
assignments, to Electronized Chemicals Corpora-
tion, a corporation of DelawareNo Drawing. Application October 9, 1945,
Serial No. 621,367

19 Claims. (CL 204—154)

1

My present invention relates to methods of producing butadiene from petroleum and fractions thereof and is disclosed in my prior U. S. patent applications Serial No. 442,136, filed May 7, 1942, which has become abandoned, for Method of Manufacturing Synthetic Rubber and Devices Therefor; Serial No. 442,137, filed May 7, 1942, which has become Patent Number 2,429,217, for Devices for Treatment of Matters with High Speed Electrons; Serial No. 442,138, filed May 7, 1942, which has become abandoned, for Method for Treatment of Matter; Serial No. 450,923, filed July 14, 1942, which has become abandoned, for Method and Means for Treatment of Perishable Substances and Products so Obtained; Serial No. 451,370, filed July 17, 1942, which has become abandoned, for Method and Means for Treatment of Vegetative Substances and Products so Obtained; Serial No. 487,179, filed May 15, 1943, which has become abandoned, for Process for Cracking Hydrocarbons by Means of Ultra High Speed Electrons; and Serial No. 488,278, filed May 24, 1943 which has become abandoned, for Preparation and Cracking of Hydrocarbons and Other Chemical Compounds by Means of Ultra High Speed Electrons to Obtain Rubber Starting Materials. Accordingly, the present patent application is a continuation in part of my above patent applications.

It is an object of my present invention to produce butadiene from petroleum and fractions thereof in a simple and inexpensive way.

It is a further object of my present invention to produce butadiene in such a manner that a great proportion of the petroleum fractions serving as initial materials are transformed into butadiene.

Still another object of my present invention consists in methods of obtaining butadiene from petroleum and fractions thereof without use of very high temperature and/or pressure as commonly employed for cracking purposes and without use of rather expensive active catalysts used in known processes of this type.

With the above objects in view, my present invention mainly consists in processes of producing butadiene from petroleum and/or fractions thereof comprising cracking of the same by bombarding the petroleum and/or their fractions with high speed electrons resulting in decomposition of the high speed electron bombarded petroleum and/or petroleum fractions and formation of butadiene.

The term "high speed electrons," as used above and in the following description and claims, is

intended to define electrons of a velocity equivalent to more than one million volts. Preferably, however, high speed electrons of a velocity equivalent to more than two million volts are employed for the processes of producing butadiene in accordance with my present invention.

In accordance with a preferred embodiment of my present invention, I treat the petroleum and/or petroleum fractions repeatedly during 10 consecutive periods with high speed electrons in such a manner that each of these repeated electron bombardments lasts less than 10^{-4} , preferably less than 10^{-6} of a second. Despite the fact that the duration of each individual electron bombardment is extremely short, averaging about 15 10^{-5} to 10^{-6} of a second, the energy displayed is 20 tremendous due to the fact that the whole energy accumulated in a condenser battery will be discharged and with the aid of the special tube will be converted into correspondingly high amounts of electronic radiation. If, for instance, the impulse generator will be charged and discharged over the discharge tube 30 times per minute and assuming that the end capacity of the generator is 8,000 centimeters and the voltage 15,000,000 25 volts, then an average electronic output of several thousand kilowatts will be obtained.

I have found that by using such short bombardment periods, it is possible to avoid almost entirely the formation of undesired unusable by-products. This is of great importance since in the commonly employed processes of producing butadiene a great percentage of the formed reaction products are such undesired substances, i. e. unusable by-products, and this constitutes the basic 30 disadvantage of all known processes.

The following petroleum fractions can be used as starting materials for the production of butadiene: paraffin base, paraffin intermediate base, intermediate paraffin base, intermediate base, intermediate naphthene base, naphthene intermediate base, naphthenic base, and others.

I have found that converting petroleum and/or fractions thereof by high speed electrons in order 40 to obtain butadiene has the following great advantages over all other known processes:

First of all, with my new process it is easily 50 possible to obtain the very great energy necessary to achieve the desired conversion of petroleum into butadiene. This great energy can be produced without the application of heat and/or pressure, i. e. in a simple way. It is also evident that the treatment with high speed electrons cannot only be carried out without diffi-

2

culties, but it is also easily possible to control and regulate the same.

Secondly, in my new process, it is possible to adjust the intensity of electron bombardment to the different initial materials and to obtain according to these different initial materials and different electron bombardment intensities different reactions in the electron bombarded petroleum and/or petroleum fractions; this in turn makes it possible to obtain higher yields of butadiene, a smaller percentage of undesired by-products and consequently easier purification of the resulting butadiene.

Third, by producing butadiene in the way proposed by me, namely by treating petroleum and/or petroleum fractions with high speed electrons, it is possible to avoid the use of expensive active catalysts and apply instead of them so-called contact materials of the type described below. In this way, it is possible to save catalysts and also to simplify the construction of the apparatus for carrying out the cracking processes and producing butadiene.

Fourth, by eliminating heat treatment and use of active catalysts, it is possible to construct the various reaction vessels and chambers of non-expensive metals instead of the heat and chemically resistant high grade alloy steels needed for these purposes so far.

I have found that it is advantageous to treat certain petroleum fractions in the vapor phase, since in this way it is possible to obtain exit gases which are very rich in mono-olefines and di-olefines; such olefines subjected to repeated electron bombardments give a high yield of butadiene.

A typical composition of such an exit gas is the following: About 9 to 16 per cent of hydrogen, methane, ethane and propane, about 24 to 28 per cent of lower molecular olefines, about 14 to 17 per cent of butene, about 10 to 12 per cent of aromatics and about 36 to 39 per cent of butadiene. Thus, it is possible to achieve by my present invention a series of reactions which tend to transform nearly all initial components of the petroleum and/or petroleum fractions into mono-olefines, di-olefines and of course also into butadiene.

I wish to emphasize, however, in this connection that my present invention is by no means limited to the cracking of petroleum fractions, since it is of course also possible to produce by this process butadiene from various petroleums themselves or from compounds which are formed during various processing operations of petroleum and/or petroleum fractions. Such compounds are for instance hydrocarbons, such as cyclohexane, cyclopentane and their derivatives, paraffin waxes, tank and still bottoms and various naptha cuts. Thus, using cyclohexane as initial material in my above described processes, it is possible to obtain a yield of pure butadiene amounting to up to 95% of the theoretical yield; in all these cases, the effect of the high speed electrons alone with which the initial materials are bombarded is over and beyond the combined effect of heat, pressure and active catalysts in the commonly used cracking processes.

It is of course also of great importance to be able to regulate the length of the reaction periods caused by the single consecutive electron bombardments. It is evident that no advantage would be attained by keeping the periods of bombardment extremely short if between these short periods the once started reactions would in part

automatically continue due to the initiation of chain reaction. In order to be able to regulate the length of the reaction periods, I have found it advisable to add, e. g. admix to the initial materials to be electron bombarded, a small percentage of agents which are adapted to prevent or at least to retard continuation of the reactions caused by the electronic bombardment after discontinuation and termination of the same. I have found that such materials called by me "contact materials" have a double effect, namely they not only retard continuation of the reaction after termination of the bombardment period but they also facilitate the energy distribution during the bombardment without being catalytically active.

I have found that for the purposes of my present invention as contact materials I may very well use various metal oxides which are not only inexpensive but also available in large amounts. In accordance with a preferred embodiment of my invention, I use in my new process as contact materials oxides of the metals of the second, third and fourth group of the periodic system, for instance, magnesium, zinc, aluminum, silicon and others.

A very material disadvantage of the use of catalysts in known processes lies in the unavoidable secondary reactions as incurred under the conditions of the standard pyrolytic processes that lead to the formation of oily polymerization products. These soon lower the activity of the catalysts so markedly that a reactivation is necessary, the oily polymers poisoning the entire active surface of the catalyst. Additional poisoning is caused by the formation of pyrolytic decomposition products due to the necessary high temperatures in standard cracking processes. Whereas the first inactivation is reversible, the second one is irreversible, thus completely destroying the activity of that part of the catalysts.

It should also be stressed that in accordance with my present invention it is necessary to use only a very small percentage of the contact material, not more than 10% of the weight of the reaction mixture. Contrary thereto, in known cracking processes it is necessary to use a great amount of highly active expensive catalysts. Compared with such known processes, the percentage of contact materials used in my processes is extremely small, not more than a few per cent of the amount of highly active catalysts being needed for thermal cracking processes. In addition thereto, it should be stressed that since these contact materials do not participate in the cracking reactions, their life is much longer than that of the catalytically active catalysts used to date.

I wish to stress again that the contact materials used for the purposes of the present invention serve a dual purpose, namely while the electron bombardment is carried out, they serve as a convenient means for increasing the reaction surface and for facilitating the energy distribution, and immediately after termination of the action of the high speed electrons these same contact materials prevent to a large extent the possibility of interaction of the highly active unsaturated compounds formed by the electron bombardment. By preventing interaction between the formed compounds, particularly the formed mono-olefines and di-olefines, after termination of the high speed electron bombardment, it is possible to obtain a small number of well defined reaction products, particularly buta-

diene, without any formation of undesired by-products caused by side reactions.

In this connection, it should also be stressed again that it is of basic importance from the point of view of the present invention that the electronic energy necessary to cause and complete conversion of the petroleum and petroleum fractions used as initial materials is applied within a split fraction of a second, thus substantially reducing the amount of undesired by-products formed during this conversion. The very low amount of oxygen containing by-products can be explained by the fact that the actual impact of high speed electrons in the formation of butadiene from petroleum is reduced to a minimal fraction of the time as compared with standard pyrolytic processes. The chance of interaction of the unsaturated compounds with the oxygen present is consequently reduced to a minimum. Thus, unsaturated aldehydes, alcohols, ketones, etc. as well as their saturated analogs are practically absent. Furthermore, the methane and ethane content of the exit gases is markedly reduced; since both these compounds are not utilizable for the preparation of any useful intermediates, this constitutes an appreciable improvement.

These factors combined, namely extremely short periods of electron bombardment combined with contact materials preventing reactions between and after these extremely short bombardment periods, make it possible that the reactions caused by such electron bombardments in accordance with my present invention result nearly exclusively in the formation of mono-olefines and di-olefines, particularly butadiene.

As mentioned above, various petroleum and/or petroleum fractions can be used as initial materials for my new processes. Thus, for instance, it is possible to also use n-butenes as initial materials for the production of butadiene. By electron bombarding such butenes, particularly 1 and 2 n-butenes, in combination with suitable contact materials of the above defined type, it is possible to obtain practical yields amounting up to 70% of the theoretical ones.

Although production of butadiene in accordance with my present invention can be carried out at room temperature, a preferred embodiment of the same consists in carrying out the bombardments at an elevated temperature, preferably at between 100 and 150° C. e. g. at 130° C. Carrying out the bombardment at such elevated temperatures is particularly advantageous if butenes are used as initial materials. In case of such initial materials the reactions consist mainly in dehydrogenation of the electron bombarded butenes; they occur—if they are carried out at elevated temperatures as set forth above—practically without any of the undesired side reactions characteristic for the commonly used de-hydrogenation processes.

I wish to stress also that I have found that by electron bombarding butenes as set forth above, I obtain reaction products which consist mainly of butadiene and contain almost no unchanged butenes at all. In addition to the formed butadiene, the thus obtained reaction products contain of course some by-products which, in turn, consist mainly of aromatics such as toluene, ethylbenzene, xylene and the like. Such aromatics are valuable per se or they may be used as intermediate products and electron bombarded again as proposed by me, thus transforming the same also into butadiene.

The reaction speed of my new process depends mainly upon the intensity of the electrons with which the initial materials are bombarded. Thus, the speed of such electrons determines the length of the time periods during which the initial materials have to be bombarded, i. e. the velocity with which the initial materials are passed through the electron bombardment zone. Thus, for instance, I found that with high speed electrons created by a 15 million volt generator, it is possible to transform about 100 gallons of butene every 15 seconds into a reaction product consisting mainly of butadiene.

In this connection, I also wish to mention that in all known de-hydrogenation processes in which intermediates are transformed into butadiene, it has been found necessary to work in an inert atmosphere in order to obtain optimal yields, because in the commonly used processes the various olefines tend to react in the presence of air to form oxygen containing by-products. Contrary thereto, in my process—due to the extremely short reaction periods made possible by the extremely great energy of the high speed electrons used for bombardment—the formation of oxidation products during and after electron bombardment is considerably reduced and practically negligible.

On the contrary, I have found that it is sometimes of advantage to carry out the bombardment of intermediate olefines such as butenes causing de-hydrogenation of the same in air or oxygen, as in this way it is possible to obtain a final product containing a high percentage of saturated and/or unsaturated alcohols, aldehydes, ketones or acids. Such substances are highly valuable themselves; however, they can also be used as intermediate materials and further electron bombarded so as to increase the final yield of butadiene.

It should be mentioned that also in case of formation of butadiene by treating butenes with high speed electrons as explained above, it is advisable to use contact materials of the above described type. The same act as stated above, namely they further and expedite reaction during each of the irradiation periods and prevent reaction between and after termination of the same.

I wish to note that I have also obtained excellent yields of butadiene by two-step electron bombardment of 2,3 dichloro-n-butene resulting in de-hydrochlorination of this initial material. I have found that in this case such a two-step de-hydrochlorination is particularly advantageous and results in nearly entire transformation of the 2,3 dichloro-n-butene into butadiene.

This process is preferably carried out by first repeatedly electron bombarding 2,3 dichloro-n-butene with high speed electrons of the above described type at moderate temperatures, preferably between 50 and 80° C., without the use of any contact material. This electron bombardment results in transformation of the 2,3 dichloro-n-butene into a mixture of mono-chloro-butenes which are then purified and then bombarded again. This second bombardment is carried out with a somewhat increased intensity, preferably at a temperature of 140 to 180° C. in the presence of contact materials of the type described above.

I have found it advisable in some cases to combine the petroleum and fractions thereof with sulphur before the high speed electron bombardment. In some cases, it has been found advisable to carry out the electron bombardment with

high speed electrons in the presence of nitrogen.

It will be understood that each of the elements described above, or two or more together, may also find a useful application in other types of processes of producing butadiene differing from the types described above.

While I have described the invention as embodied in processes of producing butadiene from petroleum and petroleum fractions, I do not intend to be limited to the details shown, since various modifications and changes may be made without departing in any way from the spirit of my invention.

Without further analysis, the foregoing will so fully reveal the gist of my invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What I claim as new and desired to secure by Letters Patent is:

1. Method of producing butadiene from a substance selected from the group of petroleum and fractions thereof comprising cracking said substance by repeatedly treating it during consecutive periods with high speed electrons of a velocity equivalent to more than one million volts, each of said consecutive periods lasting less than 10^{-4} of a second, thereby decomposing said substance and forming butadiene.

2. Method of producing butadiene from a substance selected from the group of petroleum and fractions thereof comprising cracking said substance by repeatedly bombarding it with high speed electrons, each of said electron bombardments lasting less than 10^{-6} of a second, decomposing thereby said substance and forming butadiene.

3. Method of producing butadiene from a substance selected from the group of petroleum and fractions thereof comprising cracking said substance by subjecting it to repeated treatments with high speed electrons of a velocity equivalent to more than 2 million volts, each of said treatments lasting less than 10^{-6} of a second, thus decomposing said substance and forming butadiene.

4. Method of producing butadiene from a substance selected from the group of petroleum and fractions thereof comprising cracking said substance by treating it repeatedly during a series of very short bombardment periods with high speed electrons in the presence of a contact material not participating in the chemical reaction caused by said treatment but facilitating said chemical reaction during said treatment and retarding continuation of said chemical reaction after said treatment has been discontinued.

5. Method of producing butadiene from a substance selected from the group of petroleum and fractions thereof comprising cracking said substance by repeatedly treating it during consecutive periods with high speed electrons of a velocity equivalent to more than one million volts, each of said consecutive periods lasting less than 10^{-4} of a second in the presence of a contact material not participating in the chemical reaction caused by said treatment but facilitating said chemical reaction during said treatment and retarding continuation of said chemical reaction after said treatment has been discontinued, thereby decomposing said substance and forming butadiene.

6. Method of producing butadiene from a substance selected from the group of petroleum and fractions thereof comprising cracking said substance by subjecting it to repeated bombardments with high speed electrons of a velocity equivalent to more than 2 million volts, each of said electron bombardments lasting less than 10^{-4} of a second in the presence of a contact material not participating in the chemical reaction caused by said electron bombardment but facilitating said chemical reaction during said electron bombardment and preventing continuation of said chemical reaction after said electron bombardment has been terminated, decomposing thereby said substance and forming butadiene.

7. Method of producing butadiene from a substance selected from the group of petroleum and fractions thereof comprising cracking said substance by combining it with sulphur and bombarding said mixture repeatedly during a series of very short bombardment periods with high speed electrons whereby the said substance present in said mixture is decomposed and butadiene is formed.

25 8. Method of producing butadiene from a substance selected from the group of petroleum and fractions thereof comprising cracking said substance by bombarding it repeatedly during a series of very short bombardment periods with high speed electrons in the presence of nitrogen, thereby decomposing said substance and forming butadiene.

9. Method of producing butadiene from a substance selected from the group of petroleum and fractions thereof comprising cracking said substance by bombarding it repeatedly during a series of very short bombardment periods with high speed electrons at a temperature at which said substance is in the gaseous state whereby said substance is bombarded in the gaseous phase and decomposed, resulting in formation of butadiene.

10. Method of producing butadiene from a substance selected from the group of petroleum and fractions thereof comprising cracking said substance by bombarding it with high speed electrons in the presence of contact material selected from the group consisting of oxides of metal of the second, third and fourth groups of the periodic system of elements, said contact material not participating in the chemical reaction caused by said electron bombardment but facilitating said chemical reaction during said electron bombardment and retarding continuation of said chemical reaction after said electron bombardment has been discontinued.

11. Method of producing butadiene from a substance selected from the group of petroleum and fractions thereof comprising cracking said substance by bombarding it with high speed electrons in the presence of a contact material selected from the group of metals consisting of zinc, magnesium, aluminum, boron, calcium, strontium and silicon, said contact material not participating in the reaction caused by said electron bombardment but facilitating said reaction during said electron bombardment and retarding continuation of said reaction after said electron bombardment has been discontinued.

12. Method of producing butadiene by bombarding cyclo-hexane and its naturally occurring alkyl-derivatives repeatedly during a series of very short bombardment periods with high speed electrons of a velocity equivalent to more than one

million volts, thereby cracking said cyclo-hexane and its derivatives and forming butadiene.

13. Method of producing butadiene from n-butenes comprising cracking said n-butenes by repeatedly bombarding the same during consecutive bombarding periods with high speed electrons of a velocity equivalent to more than one million volts, each of said consecutive bombarding periods lasting less than 10^{-4} of a second, thereby decomposing n-butenes and forming butadiene.

14. Method of producing butadiene from 1 and 2 n-butenes comprising cracking said 1 and 2 n-butenes by subjecting the same to repeated treatments with high speed electrons of a velocity equivalent to more than 2 million volts, each of said treatments lasting less than 10^{-6} of a second, thus decomposing said n-butenes and forming butadiene.

15. Method of producing butadiene from butenes comprising cracking said butenes by repeatedly bombarding the same during a series of extremely short irradiation periods with high speed electrons at a temperature of between 100 and 150° C., thereby decomposing said butenes and forming butadiene.

16. Method of producing butadiene comprising cracking n-butenes by bombarding the same repeatedly during a series of extremely short irradiation periods with high speed electrons thus forming a mixture comprising butadiene and aromatic substances, removing said aromatic substances and bombarding the same repeatedly with high speed electrons, thus transforming the same into butadiene.

17. Method of producing butadiene from butenes comprising dehydrogenating the same by bombarding the same repeatedly during a series of extremely short irradiation periods with high speed electrons in an oxygen containing medium, thereby decomposing said butenes and forming butadiene.

18. Method of forming butadiene from 2,3 dichloro-n-butene comprising dehydrochlorinating the same by repeatedly bombarding them during consecutive very short bombarding periods with

5 high speed electrons in the presence of a contact material not participating in the chemical reaction caused by said electron bombardment but facilitating said chemical reaction during said electron bombardment and retarding continuation of said chemical reaction after said electron bombardment has been discontinued.

10 19. Method of producing butadiene from 2,3 dichloro-n-butene comprising the steps of bombarding said 2,3 dichloro-n-butene repeatedly during a series of extremely short irradiation periods with high speed electrons at a temperature of between 50 and 80° C., thus transforming said 2,3 dichloro-n-butene into a mixture of mono-chloro-butenes, purifying said mono-chloro-butenes and bombarding the same repeatedly with high speed electrons at a temperature of between 140 and 180° C. in the presence of a contact material not participating in the chemical reaction caused by said electron bombardment but facilitating said chemical reaction during said electron bombardment and retarding continuation of said chemical reaction after said electron bombardment has been discontinued.
